UNITED STATES PATENT OFFICE.

JOHN GRIFFIN, OF GREENVILLE, MISSISSIPPI.

COTTON-PICKER.

SPECIFICATION forming part of Letters Patent No. 732,546, dated June 30, 1903.

Application filed November 12, 1901. Serial No. 81,965. (No model.)

To all whom it may concern:

Be it known that I, JOHN GRIFFIN, a citizen of the United States, and a resident of Greenville, in the county of Washington and State 5 of Mississippi, have invented a new and Improved Cotton-Picker, of which the following is a full, clear, and exact description.

This invention relates to a pneumatic cotton-picker provided with a motor and traction 10 mechanism for driving it through the fields and having an air-blast apparatus operated electrically under the control of an operator or operators.

This specification is a specific description 15 of two forms of my invention, while the claims are definitions of the actual scope thereof.

Reference is to be had to the accompanying drawings, forming a part of this specification, in which similar characters of reference indicate 20 corresponding parts in all the views.

Figure 1 is a perspective view of a complete machine. Fig. 2 is a sectional detail view of devices for controlling the air-blast. Fig. 3 is a section of the receiving end of the cotton-tube. Fig. 4 is a view of a modified form of the structure shown in Fig. 3, and Fig. 5 indicates the means for unloading cotton.

a indicates the body of the apparatus, which is mounted on traction-wheels *b* and steering-wheels *c* and is adapted to pass over the cotton-stalks.

e indicates a motor of any suitable sort, which is carried on the body *a* and connected to drive revolubly a suitably-mounted transverse shaft *e'*. From this shaft the wheels *b* are driven by sprocket-gearing *b'*.

f indicates an air-pump driven from the shaft *e'* and connected by a tube *f'* with a tank *f''*, from which the air is exhausted or 35 partly exhausted by the pump *f*.

g indicates a dynamo driven from the shaft *e'*.

c' indicates a steering-shaft connected by miter-gearing *c''* with a counter-shaft *c''*, and 45 this latter shaft is connected by sprocket-gearing *c''* with the forks of the wheels *c*.

d indicates a hopper receiving the cotton from the picking devices, to be hereinafter described. This hopper is covered by a netting *d'* and is provided (see Fig. 5) with an opening *d''* in its bottom. Commanding the opening *d''* is a closure *d''*, which swings around

the axis of a short vertical shaft *d''*, carried fast on the bottom of the hopper. On the lower end of the shaft *d''* is mounted a hoop *d''*, having spurs to engage and carry a bag *d''*. By throwing the closure *d''* sidewise the opening may be uncovered and the cotton allowed to fall from the hopper into the bag.

h indicates the cotton-picking tubes, which are formed of rubber or other flexible material and carry downwardly-opening funnels *h'*, adapted to be placed over the cotton-bolls which are to be picked. The flexible tubes *h* are joined at their upper ends to vertical sections of metallic tubes *h''*, which pass through horizontal tubes *h'''* and project upward into the hopper *d*. At the upper ends of the tubes *h''* are arranged valves *i*, which have their stems pivoted on studs *i'*, projecting out from the tubes. The stems of the valves *i* have forked extensions *i''*, connected to the stems *i'''* of flexible diaphragms *i''*. These diaphragms *i''* are arranged in cups *i''*, carried on the tubes *h''* and communicating with the interior thereof by perforations in the tubes, as shown. Should the air in the tubes *h''* be rarefied, the valves *i* will be drawn into closed position; but this tendency is partly counteracted by the drawing inward of the diaphragms *i''*. Thus the valves *i* are balanced and may be opened by slight outward pressure thereon.

i'' indicates a by-pass which is uncovered as the valve moves outward, thus permitting 85 a current of air to rush into the tube behind the cotton and accelerate its passage past the valve.

The tubes *h'''* communicate with the tubes *h''* by perforations *h''* therein and lead, respectively, to boxes *h''*, which communicate with branches *h''* of the tank *f''*. The boxes *h''* are each formed with two chambers, with the lower of which the tubes *h'''* communicate, and the upper of which are each divided by perforated partitions *k* and a flexible diaphragm *k''*. Below each partition *k* the upper chambers of the boxes *h''* are in communication with the atmosphere. Extending through the boxes *h''* are the hollow stems *k'* of the valves *k''*, which command communication between the branches *h''* and boxes *h''*. The hollow stems *k'* communicate by orifices *k''* with the spaces above the diaphragms *k''*, and said

stems are fastened to the diaphragms to move therewith. These devices serve to equalize the pressure on the valves k^2 , since by the hollow stems k' the atmospheric pressure tending to close the valves is allowed also to press upward the diaphragms k^3 , thus tending to open them. The valves k^2 seat themselves by their own weight when released from the actuating devices, to be hereinafter described.

Above each box h^4 is arranged a case l , these cases each containing a major electromagnet l' and a minor magnet l^2 . The armature l^3 of the major magnet is connected to the stem k' of the valve k^2 , so that when the magnet is attracted the valve k^2 is opened. The circuit of the magnet l' is controlled by contact devices l^4 , connected to the armature l^5 of the minor magnet l^2 , so that when the armature l^5 is attracted the magnet l' is energized. The insulated conductors (wires) from each magnet l^2 lead down the respective tubes $h^2 h$ and are in connection, respectively, with the tongue m on a finger-piece m' and a contact-block m^2 . This latter element is arranged to slide in an insulated guide m^3 , carried on the stem of the funnel h' , immediately adjacent thereto, and is actuated manually through the medium of a screw m^4 , threaded in the guide. The guides m^3 are formed with inclined ribs m^5 thereon. The tongues m are normally in contact with the blocks m^2 , but when in use the operator keeps the finger-pieces m' pressed inward toward the tubes. The tongues are thus caused to slide over the blocks m^2 and up the ribs m^5 , thus breaking contact with the blocks and breaking the circuit of which the magnet l^2 forms a part. This drops the armature l^5 , deenergizes the magnet l' , and in dropping the armature l^5 allows the valve k^2 to close. This is the position of rest of the valve devices as the machine is being drawn through the fields. To close the circuit and lift the valve k^2 , the finger m' should be released. This will cause the tongue m to slide on the block m^2 and close the circuit of which said block forms a part. Now it is clear that by adjusting the position of the blocks m^2 with respect to the ribs m^5 by the screws m^4 the instant at which the circuit of the magnet l^2 is closed may be varied at will, thus providing for closing the valve k^2 at any chosen time. The separate circuits of both magnets are energized from the dynamo g .

The circuit-opening devices shown in Fig. 3 are adapted to be operated by manual power applied directly to the finger-piece m' . In Fig. 4 I have shown an alternative arrangement which might be resorted to, if desired. By this, the circuit is closed by the mere act of placing the funnel h' over the cotton-boll, the devices being arranged in the funnel and the finger-lever m' of Fig. 3 being replaced by an arm m^6 , knuckle-jointed to the funnel h' , so as normally to hold the position shown, and adapted to be engaged and thrown inward by

contact with the cotton-boll. The other parts are exactly as previously described, excepting that the spring-finger m in Fig. 4 is normally engaged with the guides m^5 , and when the finger m^6 is pressed inward the tongue or finger m engages the contact-block m^2 . From Fig. 4 the electrical conductors have been omitted for the sake of clearness.

In the operation of the apparatus the machine is caused to be propelled through the field and one or more persons, either walking behind or riding upon the machine, carry the funnels h' in hand. The pump f is started and the tank f^2 is as nearly exhausted as possible. As the cotton-bolls are approached the funnels are placed over the bolls and the electrical apparatus manipulated, as above described, so as to open the valves k^2 . The atmospheric air now rushes into the tubes h and the cotton is instantly sucked into the tubes h . The cotton passes on at considerable velocity into the tubes h^2 , and then the valve k^2 is closed, thus stopping the air-current. This should be done immediately upon the cotton reaching the perforations h^5 in the tube h^2 , and then the cotton passes on by its momentum out of this tube h^2 past the balanced valve i , which readily opens to the pressure of the cotton. The hopper d receives the cotton from the tubes h^2 . The opening of the valve k^2 is effected (see Fig. 3) by the operator releasing the finger-piece m' immediately after the funnel is placed over the cotton or (see Fig. 4) by the cotton itself striking the arm m^6 on its way into the funnel. By means of the screw m^4 the parts may be set to work in proper time. It should be understood that it is only necessary to keep the valve k^2 open for an instant, just sufficiently to allow the cotton to nearly reach the perforations h^5 and by its momentum go on to the valve i . This mode of operation conserves power and avoids friction at the perforations.

Various changes in the form, proportions, and minor details of my invention may be resorted to without departing from the spirit and scope of my invention. Hence I consider myself entitled to all such variations as may lie within the scope of my claims.

Having thus described my invention, I claim as new and desire to secure by Letters Patent—

1. An electrically-controlled pneumatic cotton-picker, comprising the combination of a tube adapted to have the cotton passed through it said tube being perforated intermediate its ends, suction mechanism communicating with the tube through the perforations therein, said suction mechanism comprising walls forming a chamber adapted to be placed in communication with a pump, and a valve controlling the inlet to said chamber, electromagnetic means for actuating the valve, a circuit-closing device for controlling said electromagnetic means, and a wheeled vehicle on which said parts are mounted.

2. An electrically-controlled pneumatic cot-

ton-picker, comprising the combination of a tube adapted to have the cotton passed through it, said tube being perforated intermediate its ends, suction mechanism communicating with the tube through the perforations, a controlling means for the suction means, an electromagnet for actuating said controlling means, a circuit-closer for the circuit of the electromagnet, and a wheeled vehicle on which said parts are mounted.

3. A pneumatic cotton-picker, comprising a tube adapted to have the cotton passed through it, said tube being intermediately perforated, suction means communicating with the tube at the perforation thereof, a valve commanding the discharge end of the tube, a cup located adjacent to the discharge end of the tube and communicating with the interior thereof, said cup including a diaphragm arranged therein, and a connection between the diaphragm and the valve.

4. A pneumatic cotton-picker, comprising a tube adapted to have the cotton passed through it, said tube being intermediately perforated, a suction device communicating with the tube through said perforation, a valve commanding the discharge end of the tube, and walls forming a by-pass opening into the tube intermediate the said perforation and the valve, said by-pass being closed by the valve simultaneously with the closure of the tube thereby.

5. An electrically-controlled pneumatic cotton-picker, comprising a tube adapted to have the cotton passed through it, said tube being intermediately perforated and having at one end a receiving-funnel, a suction apparatus communicating with the tube through the perforation therein, electromagnetic devices controlling the suction apparatus, and contact devices for the said electromagnetic devices, the contact devices being located in the funnel to be operated by the pressure of the cotton.

45 6. A pneumatic cotton-picker, comprising a tube adapted to have the cotton passed through it, said tube being intermediately perforated, a tank, a pump communicating with the tank, a tube establishing communication between the tank and the perforation of the tube, for the purpose specified, a valve

commanding such communication, a hollow stem attached to said valve, a diaphragm attached to the stem, a box in which said diaphragm is located, the diaphragm dividing the box into two chambers, one of said chambers being in communication with the atmosphere and the other chamber being in communication with the interior of the hollow stem, and means for operating the valve.

60 7. An electrically-controlled pneumatic cotton-picker, comprising the combination of a tube adapted to have the cotton passed through it, said tube being perforated intermediate its ends, suction mechanism communicating with the tube through the perforations thereof, said suction mechanism comprising walls forming a chamber, a pump, communicating with said chamber, a valve controlling the inlet to said chamber, electromagnetic means for actuating the valve, a circuit-closing device for controlling said electromagnetic means, a wheeled vehicle on which said parts are mounted, and means for driving the pump from a mobile part of the vehicle.

8. A pneumatic cotton-picker, comprising a tube adapted to have the cotton passed through it, said tube being intermediately perforated, a tank, a pump communicating with the tank, a tube establishing communication between the tank and the perforation of the tube first named, for the purpose specified, a valve commanding such communication, a hollow stem attached to said valve, a diaphragm attached to the stem, a box in which said diaphragm is located, the diaphragm dividing the box into two chambers, one of said chambers being in communication with the atmosphere and the other chamber being in communication with the interior of the hollow stem, means for operating the valve, a wheeled vehicle on which said parts are carried, and means for operating the pump from a mobile part of the vehicle.

95 In testimony whereof I have signed my name to this specification in the presence of two subscribing witnesses.
